LOCOMOTIVE DRAFTING PLANT

Original application filed September 14, 1925, Serial No. 56,113. Patent No. 1,669,455, dated May 15, 1928.
Divided and this application filed June 13, 1927. Serial No. 198,510.

This is a division of my application for patent on a system of drafting locomotives in roundhouses, Serial No. 56,113, filed September 14, 1925, Patent No. 1,669,455, May 15, 5 1928.

This invention relates to drafting of locomotives in roundhouses during the firing up period, but it is capable of general use, particularly certain parts of it.

10 The principal objects of the invention are to eliminate the usual steam pipe with which roundhouses are now provided; to substitute for it mechanism for drafting locomotives in the different stalls of a roundhouse or any 15 other place where locomotives may be drafted such as repair sheds, railroad yards, sidings, etc., by a portable blower to be attached to or placed on the stack of a locomotive and to discharge the gases of combustion into the 20 smoke jack or uptake through the roof of the roundhouse or into a stack or chimney, or directly into open atmosphere; to provide means for quickly transferring the blower from one locomotive to another; to provide 25 the blower with a suitable support to place it on the stack of the locomotive regardless of the position of the locomotive in relation to the smoke jack or gas uptake; to provide means for connecting the blower with the top of the 30 smoke jack regardless of the height of the locomotive; to provide supporting means for the blower in case the locomotive should be backed out of the roundhouse while the blower is on the stack of the locomotive; and to 35 provide means for fitting the blower on different sizes and heights of locomotive stacks.

Other objects and advantages of the invention will appear hereinafter.

Reference is to be had to the accompanying 40 drawings in which

Fig. 1 is a plan of a part of a roundhouse indicating several stalls and illustrating the overhead tracking arranged according to this invention and its relation to the smoke jacks 45 but without illustrating details;

Figs. 2 and 3 are a plan and side view showing a way of providing for the pivotal arrangement of the spur track;

Figs. 4 and 5 are end and side views of a 50 blower to be used;

Fig. 6 is an enlarged sectional view of the adjustable blower intake;

Figs. 7 and 8 are views similar to Figs. 4 and 5 showing another form in which a part of this invention can be carried out;

Figs. 9 and 10 are similar views of another form;

Fig. 11 is an enlarged sectional view on the line 11—11 of Fig. 9; and

Fig. 12 is an enlarged sectional view on the line 12—12 of Fig. 9.

Every time the boiler of a locomotive is cleaned and inspected, which is done at least once a month, a new fire must be started in the locomotive, and steam pressure built up. When minor repairs are made in the locomotive fire box, while the locomotive boiler remains under steam pressure, air is induced through the locomotive fire box by creating a draft in the locomotive stack. This is normally done by a steam jet blower with which each locomotive stack is equipped, and usually steam for operating this steam blower is taken from a steam main in the roundhouse. This means that a steam connection must be made through a flexible hose or steam pipes with flexible couplings. This method is very costly and cumbersome. The advantages of a blower system are fully appreciated, but heretofore blower systems have always been of a stationary nature, the stack being connected by flexible or telescoping pipes to the blower intake. The blower then discharges the gases of combustion, or the air induced through a chimney. This system has been found very costly to maintain, cumbersome in operation, and tending to a waste of power on account of the tendency of the operator to leave the blower intakes open, thereby using needlessly much power.

With my system I provide a small motor driven blower which takes care of one locomotive at a time, but may be used in any one stall of the roundhouse. A number of such blowers may be used side by side or widely scattered over the roundhouse thereby giving the utmost flexibility of operation. For this purpose I provide a monorail system from one end of the roundhouse to the other, with a spur leading to each stall of the roundhouse,

these spurs being connected to the main rail by two way switches.

In Fig. 1 I have shown part of a roundhouse diagrammatically with a monorail system having a number of stalls each with a smoke jack 113 as usual, I-beams 114 constituting the main rail and there are a series of spurs 125 hinged at 126 so that the blower may be moved slightly to the left or right to take care of any tilting of the locomotive stack. This can be done by chains 120 or the like. The free end rests and slides on a horizontal bar 124. In this case the track normally moves directly under the smoke jack 113. I have shown in Figs. 2 and 3 how the rail 125 can be pivoted on the stud 126. The pivot stud is mounted on a plate 123 secured to the bottom of a stationary rail 127. Overlapping plates 128 and 129 are secured to the tops of the rails 125 and 127.

The blower casing is located in inclined position, in Figs. 4, 5 and 6. The intake 130, instead of being fixed rigidly to the blower casing, telescopes with one or more sections 25 or collars 131. These sections are moved up and down by two chains or ropes 132 running over quadrants 133, one of the quadrants having an arm 134 with a chain 135 to operate it from the floor. Therefore, instead of moving the blower up and down, only the intake is moved up and down and no hoist is necessary. The blower is suspended by a link 136 pivotally depending from a trolley.

In the form shown in Figs. 7 and 8 the blower casing is suspended by chains 8 and a yoke 8^a fulcrumed at 8^b in a lug 8^c of the blower casing. The chains 8 are the load chains of a geared trolley hoist 9, the trolley of which runs over the spur 125 of the monorail system which is suitably supported by hangers. The jack 11 is provided with doors 12 which are pulled open by a chain 13 over a pulley sufficiently to allow the blower to enter the smoke jack. After the blower has entered the smoke jack the doors are allowed to close by their own weight or by suitable springs or counter-weights, not shown, provided for the purpose. The track or spur 125 passes through the doors 12 and through an opening 7 in the opposite wall. The blower has a conical intake 15 which rests on the locomotive stack, the blower being moved up and down by the operating chain 16 of the hoist. By means of a chain 121 the blower can be swung about the chains 8. By operating the chain 17 of the geared trolley the blower is moved in or out of the jack.

Figs. 9 to 12 show the blower with a screw hoist instead of a chain hoist, as previously described. The screw hoist is pivotally supported from the trolley. The blower is suspended from the screw rod 29, fulcrumed at 21 so that it can swing slightly out of its normal position in order to set squarely on the locomotive stack if the locomotive should be

tipped to one side. Bracket 22 which is fastened to the blower outlet, has a fork 23, the arms of which are guided by the flat sides of the housing 24 of the screw hoist so that the blower and the hoist rod 25 are prevented from turning around the center of the rod.

The blower itself consists of a housing 30 having an intake elbow 31 provided with a flared inlet 32. To the upper part of the blower housing is bolted a fan casing 33 with a hub 34 containing a bearing bushing 35 through which passes the shaft 36. The bushing 35 is provided with prongs or ribs on the outside so that air passages 37 are formed between the hub 34 and the bushing. The hub 34 is fastened to the casing 33 by means of ribs 34^a and between these ribs are gaps 34^b which are closed by covers and thus constitute air passages. The inlet to the air passages 37 is closed by a pipe 40 and the inlet to the air passages 34^b is closed by a flat plate 41 and a pipe 42. This forms an air passage between the pipes 40 and 42 which communicates with the atmosphere outside of the blower. An air passage is also formed between the pipe 40 and the shaft 36 communicating with the passages 37 and opening up to the motor casing. By the action of the fan 38 air is drawn from the outside between the pipes 40 and 42 and also through the motor and around the shaft. At the extreme end of the shaft is the fan 38 discharging the gases into the blower outlet 39.

On the other end of the housing 30 is bolted the motor frame consisting of a cap 43, shell 44, and cap 45, the latter containing the other bearing of the blower. Thus the motor is located out of the path of the heated gases of combustion. The lubrication of this bearing is furnished by an ordinary grease cup screwed into the cover 48 and the grease pipe for the upper bearing is located inside of a sleeve which is screwed into the hub 34 so that there is an air passage between this pipe and the grease pipe for keeping the grease cool. A guard 46 protects the motor.

The casing 30 is provided with two doors 47, one on each side, which, when the blower is not in operation, hang open as indicated, but when the blower is started up a suction is created inside of the blower housing, which automatically closes these doors. These doors are for the purpose of letting cold air into the blower housing if the blower should be allowed to remain on a stack not in operation, thereby reducing the temperature of the gases and consequently the heat to which the bearing 35 is subjected. The motor is provided with long wires for plugging in the motor at a convenient place for each stall.

With all these constructions, the steam pipes with which roundhouses are ordinarily equipped for the purpose of drafting the locomotives are entirely eliminated. This also eliminates the expense of installation and up-

keep of these pipes and their supply from the boilers. The blower is held up, if the locomotive is moved out when nobody is attending to the blower particularly, so that no damage is likely to be done from any in-
 5 attention of that kind. The portable blower is easily fitted to the stack of the locomotive even if the stack is not centrally located under the jack or if it is tilted to one side. This is a
 10 material improvement over the blower systems that have been installed heretofore because the blower is portable and no flexible or telescoping pipes have to be used in connection with it that may be left open, thus wast-
 15 ing power.

Although I have illustrated and described three forms of the invention, I am aware of the fact that other modifications can be made therein by any person skilled in the art with-
 20 out departing from the scope of the invention as expressed in the claims.

Therefore I do not wish to be limited in these respects but what I do claim is:—

1. In a locomotive roundhouse, the combi-
 25 nation with the smoke jacks, of a main track, a series of spurs extending inwardly from the main track to the several stalls of the round-
 house under the smoke jacks, a series of pivots connecting the spurs with the main track so
 30 that the spurs can be swung about in a horizontal plane, and a portable blower supported by and movable along the track and any of the spurs.

2. In a locomotive drafting plant, the combi-
 35 nation with a main track and a series of spurs pivotally connected with the main track, of a portable blower depending from and movable along under the track and also movable on said spurs, smoke jacks through
 40 which the several spurs are located, and doors for the smoke jacks to allow the blower to enter the jack.

3. In a locomotive drafting plant, the combi-
 45 nation with a smoke jack having a door, a track extending into the jack, and a blower supported from the track and movable into the jack through the door.

4. In a locomotive drafting plant, the combi-
 50 nation with a smoke jack, and a track capable of being located in vertical alignment therewith, of a blower supported by the track and movable along it into registration with the jack.

5. The combination with a smoke jack, of
 55 a blower for application to a locomotive smoke stack and adapted to direct the gases therefrom upon into the jack, means for supporting the blower within the bottom of the jack pivotally on horizontal and vertical axes, said blower comprising a casing with an open mouth at the bottom slanting and conical to receive the top of a smoke stack, and a motor for driving the blower located below the casing and outside its intake.

6. In a locomotive drafting plant, the com-

bination with a smoke jack, of a track pivoted at one end to swing on a vertical axis, and a transverse horizontal bar on which the free end of the track rests, the track being located under the jack.

7. In a locomotive drafting plant, the combi-
 70 nation with a locomotive smoke stack, of a track pivoted so that it can be swung about in a horizontal plane, and a portable blower supported by and movable along the track toward the stack.

8. In a locomotive drafting plant, the combi-
 75 nation with a locomotive smoke stack, of a stationary track, a pivoted track connected with the stationary track so that the pivoted track can be swung about in a horizontal plane, and a portable blower supported by and movable along the stationary track and the pivoted track toward the stack.

9. In a locomotive drafting plant, the combi-
 80 nation with a locomotive smoke stack, of a track pivoted so that it can be swung about in a horizontal plane, a trolley on said track, means for moving the trolley along the track, a vertical support depending from the trolley and capable of turning on its vertical axis, and a blower pivotally connected on a horizontal axis with said support, whereby the blower can be turned about said vertical axis and swung on the horizontal pivot to bring it into proper relation to the smoke stack beneath.

10. In a locomotive drafting plant, the combi-
 85 nation with a locomotive smoke stack, of a stationary track, a pivoted track connected with the stationary track so that the pivoted track can be swung about in a horizontal plane, a trolley on said track, means for moving the trolley along the track, a vertical support depending from the trolley and capable of turning on its vertical axis, and a blower pivotally connected on a horizontal axis with said support, whereby the blower can be turned about said vertical axis and swung on the horizontal pivot to bring it into proper relation to the smoke stack beneath.

11. In a locomotive roundhouse, the combi-
 90 nation with a smoke jack thereof, of a track under the smoke jack and a portable blower supported by and movable along the track, and means whereby the blower can be moved universally to any desired position under the jack.

12. In a locomotive drafting plant, the combi-
 95 nation with a smoke stack, of a bodily movable track located under the jack, a blower supported by said track and movable horizontally into any position under the smoke jack and adapted to be adjusted to the stack of a locomotive under the jack.

13. In a locomotive drafting plant, the combi-
 100 nation with a track and a smoke jack located over the track, of a blower, means located under the jack for adjustably sup-

porting the blower, said means being capable of allowing the blower itself to be moved to any position under the jack, and means whereby the blower can be adjusted to fit on smoke stacks of different sizes and kinds:

- 5 14. In a locomotive roundhouse, the combination with a smoke jack thereof, of a track below the smoke jack movable horizontally and a portable blower supported by and movable along the track.
- 10 15. In a locomotive drafting plant, the combination with a smoke jack, of a track pivoted at one end to swing on a vertical axis, and supporting means for the free end of the track capable of allowing the track to be moved in a horizontal plane, the track being located under the jack.
- 15 16. In a locomotive drafting plant, the combination with a smoke jack, of a track pivoted so that it can be swung about in a horizontal plane, and a portable blower supported by and movable along the track toward the jack.
- 20 17. In a locomotive drafting plant, the combination with a smoke jack, of a track pivoted so that it can be swung about in a horizontal plane, a portable blower movable along the track and means for bringing the outlet of the blower into registration with the smoke jack.
- 25 18. In a locomotive drafting plant, the combination with a locomotive smoke stack, of a track pivoted so that it can be swung about in a horizontal plane, a portable blower movable along the track and means for bringing the inlet of the blower into registration with the top of the smoke stack.
- 30 19. In a locomotive drafting plant, the combination with a smoke jack, of a track movable horizontally and a portable blower supported by and movable along the track to and from the smoke jack.
- 35 20. In a locomotive drafting plant, the combination with a locomotive stack, of a track movable horizontally and a portable blower supported by and movable along the track to and from the smoke stack.

In testimony whereof I have hereunto affixed my signature.
